UNITED STATES PATENT OFFICE.

OTTO SCHOELLER, OF COLOGNE, GERMANY.

COIN-CONTROLLED CYCLE-HOLDER.

SPECIFICATION forming part of Letters Patent No. 614,897, dated November 29, 1898.

Application filed December 29, 1897. Serial No. 664,474. (No model.)

To all whom it may concern:

Be it known that I, OTTO SCHOELLER, engineer, a subject of the King of Prussia, German Emperor, residing at Bonnerstrasse 14, 5 Cologne, German Empire, have invented new and useful Improvements in Automatic Paying Machines for the Secure Fastening of Cycles, of which the following is a specification.

The invention now to be described is an 10 apparatus which renders it possible by dropping in a coin to set in motion a mechanism by means of which a cycle can be locked to a post or similar support.

In the drawings, Figure 1 is a transverse 15 section through the device. Fig. 2 is a section taken from front to rear. Figs. 3 and 4 are details relating to the permutation devices.

The apparatus works in the manner of an 20 alphabet-lock and has the following construction: The coin after being dropped into the slot II reaches the position *a'* between the back *b* of the case and the arm *c* of the angle-lever *c d*.

Above the coin *a* slide *e* is fixed, which can 25 be moved from the outside by the button *f* and which is held up by a spring *g*. When the slide *e* is pushed down by pressure on the button *f*, it rests upon the coin *a*, which gradually takes the position *a'*, bringing the angle-lever *c d* into the position indicated, thus 30 driving the shoulder *h* along with the bar *m* while overcoming the resistance of the spring *i* out of the notch *k* of the latch-detent *l*.

The latch-detent *l* is acted upon by the 35 spring *n*, which tends to keep it in the position designated. Between the latch-detent *l* and the spring *n* there is the arm *o* of the angle-lever *o p*, which carries on the other arm *p* the tumblers *q*. The tumbler catches before 40 hind the nose of the hook *E*, which is attached to the end of the chain *C*, passing round the cycle.

The point *E'* of the hook *E* when pressed in forces up the tumblers *q* on the lever *p*, overcoming the resistance of the spring *n*. The hook is, however, prevented from being withdrawn by the tumbler *q* dropping down into place. The latch-detent *l* is guided in a shoulder *s*, attached to the front side of the case. 45 It has noses *l'*, which in the rings *r* correspond to the grooves *r'*. In the position given of

the latch-detent *l* these noses *l'* allow of the turning of the rings *r*. The rings *r* have in the full parts *r²* notches *r³*, (see Fig. 3,) into which the noses *l'* can be pressed when the 55 notches *r³* are all placed in the same direction as that of the noses *l'* of the latch-detent *l*. It then becomes possible to press in the latch-detent *l*, overcoming at the same time the resistance of the spring *n*. On the 60 rings *E* are placed other rings *r⁴*, which can be turned around the rings *r* when the noses *l'* of the latch-detent *l* are resting in the notches *r³* of the rings *r*. Then the points *r⁵* on a spring *r⁶* slide over the points in the rings *r⁴*. Should, on the other hand, the latch-detent *l* be in the position shown in the drawings, the points *r⁵* can be carried around with the points *r⁷* of the rings *r⁴*, and in that case the rings *r* indiscriminately prevent the sliding back of the latch-detent *l*. When at rest, the latch-detent *l* is pressed back, when the pins *l'* remain in the notches *r³* of the rings *r*. In this position the shoulder *h* of the draw- 65 rod *m* also rests, moving to the pressure of the 70 spring *i* in the notch *k* of the latch-detent *l*, the spring *n* being extended.

If now a cycle is to be secured, the rings *r⁴* are placed on certain selected numerals, forming a number which must be remembered. 80 As the rings *r* are prevented from turning by the pins *l'*, the points *r⁷* slide over the points *r⁵* until the points are reached corresponding to the selected number of the ring in question. If one now drops a coin into the slot 85 II and presses the slide *e* by the button *f*, the lever-arm *c* of the double lever *c d* gives way and the shoulder *h* of the rod *m* frees in coming down the latch-detent *l*. By the action of the spring *n* the detent is pressed outward, 90 and now the rings *r* can be turned around at pleasure, as now the pins *l'* correspond with the grooves *r³* of the rings *r* and are no longer held in the notches *r³*. At the same time with the latch-detent *l* the lever-arm *o* has 95 been moved by the spring *n*, and the hook *E* on the chain *C* can be held by the tumblers *q* of the lever *p*. When the chain is again to be unloosed and the cycle set free, the rings *r⁴* must be again arranged to the selected number. In this case the notches *E'* 100 correspond with the pins *l'* of the latch-de-

tent l and allow of the latter being pushed back. By this the pressure of the spring n is overcome and the tumblers V lifted up from the hook E . At the same time the shoulder h of the rod m slips into the notch k of the latch-detent l , in which position it is held fast until by the dropping in of another coin the machine is again utilized. With the latch-detent l in this position the rings r^4 on the 10 rings r can be turned at pleasure, so that the number before fixed on is no longer apparent. The indentation k has a shoulder k' , whose purpose is to check the latch-detent l and the inner rings r even when the former has not 15 been pushed in entirely.

I claim—

1. In combination in a lock for bicycle-stands and the like, comprising a casing, a hook or bolt adapted to be inserted therein, 20 locking mechanism in the said casing to engage said hook or bolt, and coin-freed and permutation mechanism for controlling the said locking mechanism, substantially as described.
2. In combination in a lock, the casing, a bolt or hook adapted for insertion therein, a locking device within the casing acting on 25 said hook or bolt, a releasing device, and coin-freed and permutation mechanism for

controlling the said releasing device, substantially as described. 30

3. In combination, the casing, a hook or bolt adapted to be inserted therein, locking mechanism in said casing to engage said hook or bolt, coin-freed mechanism and manually- 35 operated means for controlling said locking mechanism after the coin-freed mechanism has been operated, substantially as described.

4. In combination, the casing, the hook E , the locking device therefor, the slide e controlling the locking device, the coin-freed mechanism for controlling the slide consisting of the bar m and the lever c , said bar being adapted to engage and hold the slide and a permutation device for controlling the slide 40 consisting of rings r r^4 set in pairs and coupled together by notches r^7 and elastic points r^5 , the inner of said rings having notches r^3 to receive pins l' on the slide, substantially 45 as described. 50

In testimony that I claim the foregoing as my invention I have signed my name in presence of two subscribing witnesses.

OTTO SCHOELLER.
